ton, Del., a corporation of Delaware

Application April 14, 1944, Serial No. 531,056

2 Claims. (Cl. 286—17)

1

This invention relates to seal structures that are adapted to seal upon a moving member that operates through a wall of a chamber containing fluid under pressure to prevent leakage of the fluid from the chamber. More particularly, the invention relates to a seal structure adapted to be used around the ram of a hydraulic press to seal the ram at its point of exit from the ram cylinder and thereby prevent leakage of hydraulic fluid around the ram.

According to the conventional practice in the manufacture of hydraulic presses, it has been, and is, the conventional practice to provide a seal member around the ram that is sufficiently tight to prevent any and all leakage of hydraulic fluid from the ram cylinder. There is a definite attempt to run the ram dry, because any leakage of hydraulic fluid around the ram of the hydraulic press causes the oil to run over the press, and in general produce a very disagreeable working condition. It is not unconventional for pressures as high as 2,500 lbs. per square inch to be used in the main cylinder areas of the ram for operating the same. Therefore, to resist leakage of fluid around the ram it has required the development of special seal structures that are in intimate contact with the surface of the ram with sufficient pressure applied thereupon to prevent the high pressure in the ram cylinder areas from leaking past the seal member.

The result of prior ram seal structures has therefore resulted in the operation of a substantially dry ram, having regard to the working surfaces between the ram and the seal member. Such dry working surfaces are not efficient in operation because considerable friction is developed between the ram and the seal surfaces which prevents freedom of movement of the ram, and in conventional rapid traverse presses the friction between the seal and the ram has in many instances been sufficient to prevent the ram from falling freely during the rapid traverse movement. This is noticeably true in small presses.

Also, the operation of a ram having dry surfaces over a seal member that is also provided with a dry surface results in a scoring of the surface of the ram. Scoring of the ram in turn cuts the surface of the seal, and as a final result leakage of hydraulic fluid from the press increases at an ever-increasing rate as the operation of the press continues.

It is therefore an object of this invention to provide a seal structure for a ram of a hydraulic press that is constructed and arranged in a manner that hydraulic fluid from the hydraulic circuit can continuously flow past the seal to provide

2

a film of lubricating oil between the ram surface and the seal, the oil flowing past the seal surface being continuously returned to the reservoir of the hydraulic circuit.

- 5 Still another object of the invention is to provide a seal for a ram of a hydraulic press wherein the seal member is constructed and arranged in a manner that leakage of a predetermined quantity is provided past the sealing surfaces to permit 10 lubrication thereof, which fluid leakage is returned to the reservoir of the hydraulic system, and wherein the seal structure is adapted to wipe the surface of the ram clean before it enters the seal structure, thereby preventing dirt and grit 15 from entering the seal structure which would tend to grind or wear the surface of the ram and cut the seal packing material.

- Still another object of the invention is to provide a seal structure for a ram of a hydraulic 20 press that is constructed and arranged to permit a normal or predetermined leakage past the seal for normal lubrication of the ram surface when operating in the seal structure and which is also constructed and arranged to return all leakage 25 fluid to the reservoir of the hydraulic system including any abnormal fluid leakage past the seal structure that should occur due to abnormal conditions.

- Still another object of the invention is to provide a seal structure for the ram of a hydraulic press wherein the ram can operate within the seal structure under a condition wherein the seal structure is flooded with oil to provide lubrication of the ram while therein and yet that part of the 35 ram outside the seal structure will have a relatively dry circuit to thereby prevent oil from the hydraulic surface from running over the press body and causing unsatisfactory working conditions.

- 40 Further objections and advantages will become apparent from the drawings and the following description.

In the drawings:

- Fig. 1 is a cross-sectional view of a hydraulic press illustrated somewhat diagrammatically to show the application of the seal structure of this invention to the same.

- Fig. 2 is an enlarged cross-sectional view of the seal structure of this invention illustrating the manner in which fluid flowing through the seal structure is removed therefrom for return to the reservoir of the hydraulic system.

- Fig. 3 is an enlarged perspective view of the 55 wiper ring that forms a part of the seal structure of this invention.

Fig. 4 is a cross-sectional view of the seal structure of this invention illustrating the manner in which the wiper ring is retained in position.

Fig. 5 is a cross-sectional view of a slightly modified form of the seal structure of this invention.

Fig. 6 is a cross-sectional view of a further slightly modified form of the seal structure.

Fig. 7 is a cross-sectional view illustrating the manner in which the ends of the wiper ring are secured together.

Fig. 8 is a plan view of the wiper ring illustrated in Fig. 7 showing the fastening means therein.

Fig. 9 is a cross-sectional view of the wiper ring as illustrated in Fig. 5 showing a modified arrangement thereof.

Figure 10 is a cross-sectional view of an arrangement of the wiper ring constructed with a separate seal member.

Figure 11 is a cross-sectional view illustrating the unconfined form of the wiper ring illustrated in Figure 10.

The seal structure of this invention is applicable to the ram of a hydraulic press as diagrammatically illustrated in Fig. 1. As illustrated, the hydraulic press consists of a ram 10 having a piston-head 11 that reciprocates within a cylinder 12 that has the cylinder bore 13 to receive the piston-head 11.

A seal member 15 is disposed between the ram 10 and a recess 14 provided in the lower end of the cylinder bore 13. The seal member 15 therefore seals or closes the space 16 provided between the ram 10 and the cylinder bore 13 which receives fluid under pressure through the conduit 17. The fluid under pressure in the space 16 acts upon the lower surface of the piston-head 11 for producing a retraction movement of the ram 10. The upper chamber 18 of the cylinder 12 is supplied with fluid under pressure through a conduit 19. The conduits 17 and 19 are connected to a suitable source of fluid under pressure such as a reversible variable delivery pump that supplies fluid to either of the conduits 17 and 19 in response to controls that are well known in the art.

The seal members 15 used around the press ram 10 have heretofore been constructed and arranged to prevent any leakage from the chamber 16 along the wall of the ram 10 in an attempt to keep the lower portion of the ram dry. The seal structure of this invention, however, permits a controlled flow of hydraulic fluid, such as oil, past the seal member along the wall of the ram 10 to provide for lubrication of the same, and conducts the fluid away from the ram so that the lower portion thereof can still operate as a dry ram but with suitable lubrication provided over the area that is in contact with the seal member 15.

The structure of the seal member 15 is more specifically disclosed in Figs. 2, 3 and 4. As disclosed in these figures the ram 10 operates within the cylinder 12 and the seal member 15 is disposed within the recess 14 provided in the lower portion of the cylinder bore 13.

The seal structure consists of an upper retaining ring 20 that is made from metal and is disposed between the ram 10 and the wall of the recess 14. The retaining ring 20 is held in position by the inter-engaging taper surfaces 21 provided on the ram 10 and the wall of the recess 14.

A plurality of packing rings 22 are positioned in the recess 14 around the ram 10. These pack-

ing members 22 are known in the art as V-packing members. The straight sidewalls 23 and 24 of the packing members 22 engage the surface of the ram 10 and the surface of the recess 14 to thereby seal against the same when pressure is applied upon the packing members 22. The packing members 22 are conventionally made from linear packing material that is cut to the desired length to circumferentially enclose the ram 10, the ends of the packing members 22 being suitably tapered or scarfed to provide an effective sealing across the ends of the packing members at their juncture.

Each of the packing members 22 is constructed with a substantially U-shaped bottom section 25 that is adapted to engage the upper V-shaped flat surface 26 of the packing member that is disposed beneath the same. The association of the V-shaped bottom sections of the packing members with the V-shaped top sections thereof therefore provides small space areas 27 between the edges of the packing members and along the center portions thereof.

A gland ring 28 is inserted in the space between the wall of the recess 14 and the wall of the ram 10 to engage the lowermost packing member 22. This gland ring 28 is retained in the position illustrated in Figs. 2 and 4 by means of a retaining ring 29. The retaining ring 29 is suitably secured to the wall 12 of the cylinder by means of bolts, studs or nuts 30. These bolts are tightened sufficiently upon the retaining ring 29 to cause the gland ring 28 to apply pressure upon the packing members 22, to compress the same, to place the edges 23 and 24 of the packing members 22 in relatively tight frictional engagement with the wall of the recess 14 and the wall of the ram 10. The degree of compression of the packing members 22 will control the quantity of hydraulic fluid that is permitted to flow between the edges of the packing members 22 and the walls that they engage.

In the usual and conventional construction of seal members, the gland ring 28 is moved upwardly until the packing members 22 are compressed to an extent that the pressure applied thereupon causes sufficient frictional engagement thereof with the wall of the recess 14 and the wall of the ram 10 that hydraulic fluid from the chamber 16 is prevented from leaking through the packing members. This, therefore, requires a relatively high compression of the packing members 22 and produces high frictional engagement between the packing members 22 and the wall of the ram 10 which wipes the wall of the ram 10 dry as it passes across the surface of the packing members 22. The dry working surface of the ram 10 is therefore scored as a result of its movement across the surface of the packing members 22. Any oil leaking past the packing members 22 would, in a conventional hydraulic press, run down the surface of the ram and flow over the dies. If the leakage is not stopped promptly, by the replacement of the packing members, it continuously becomes worse as long as the press is operated under these conditions.

In the seal structure of this invention there is provided a wiper ring 31 that is provided for collecting and directing a controlled flow of fluid past the seal members 22 so that the controlled leakage can be returned to a supply reservoir of the hydraulic system through the conduit 32. The wiper ring 31 is shown in more detail in Fig. 3 that illustrates a cross-sectional view of the wiper ring when in relaxed condition.

The wiper ring 31 is provided with a plurality of

longitudinally extending ridge portions 33 that are substantially V-shaped in cross-section. It will be noted that the transverse cross-section of the wiper ring 31 has a general arcuate contour, and that the apex of each of the V-shaped segments 33 extends toward the axial center of the general arcuate contour of the wiper ring 31. The plurality of V-shaped segments 33, therefore, provides a plurality of longitudinally extending recess areas 34 that provide chambers to receive hydraulic fluid when the wiper ring cooperates with the ram in a manner to be hereinafter described.

The wiper ring 31 has the V-shaped segments 33 disposed on one side of the longitudinal center thereof positioned with the apex of each of the longitudinally extending segments positioned toward the outer edge of the wiper ring 31. Thus, the segments 33 are positioned in an opposite direction to the segments 33a so that the segments 33 will produce a squeegee operation or function upon the surface of the ram 10 when it moves in one direction and the segments 33a will produce a similar squeegee function upon the surface of the ram 10 when it moves in an opposite direction. The wiper ring 31 is provided with a longitudinally extending ledge portion 35 that cooperates with the body 36 thereof to form a recess 37 that is provided for the purpose of cooperating with the retaining ring 29 to hold the wiper ring 31 in position in the manner illustrated in Fig. 4.

The wiper ring is preferably constructed of one of the synthetic rubber-like materials, such as Duprene, neoprene, Buna S or any of the other synthetic rubber-like materials that are resistant to oil.

The wiper ring 31 can be produced as an extruded article of manufacture in any desired length, and can be cut to a length desired that will encompass the ram 10. The abutting ends of the wiper ring 31 may be secured together, in abutting relationship, by means of metal wires or nails 38 as illustrated in Figs. 7 and 8.

The wiper ring 31 is positioned within a recess 39 provided in the gland ring 28 and a cooperating recess 40 provided in the retaining ring 29. When the wiper ring 31 is in position as illustrated in Fig. 4 the general arcuate contour of the ring, as illustrated in Fig. 3 is straightened out into the flat contour illustrated in Fig. 4. The flexing, or straightening, of the contour of the wiper ring 31 produces a pressure upon the surface of the ram 10 to retain the wiper ring 31 in frictional engagement with the surface of the ram 10.

The recesses 39 and 40 provide a chamber that receives the wiper ring 31 that is substantially larger, in length, than the wiper ring 31. The space 41 in the upper portion of the chamber forms an annular space around the ram 10 between the wiper ring 31 and the gland ring 28 into which the hydraulic fluid that flows, or leaks, past the seal members 22 enters. A similar space 42 is provided beneath the wiper ring 31, and communicates with the atmosphere directly through a passage 43.

The annular space 41 is connected to the conduit 32 by means of a passage 44 provided in the gland ring 28 and a fitting 45 that extends into a passage 46 provided in the retaining ring 29. The conduit 32 communicates with the passage 46 in the retaining ring 29. Also, the conduit 32 is adapted to be connected to the fluid supply reservoir for the hydraulic system that supplies fluid under pressure to the cylinder 12

of the press. It will therefore be seen that the annular space 41 is a space of relatively low pressure, if any, because the conduit 32 is connected with the exhaust side of the hydraulic system, which is open to the atmosphere.

The gland ring 28 is provided with an annular recess 47 that receives a circular ring 48 of rubber-like material, which can be one of the synthetics previously mentioned, has the ends thereof in abutting relationship so that when slight pressure is applied upon opposite sides of the ring to slightly deform the same, the engagement of the ring with the recess 47 and the wall of the recess 47 will prevent fluid passing downwardly along the wall surface of the recess 47. A passageway 49 is provided between the recess 47 that receives the seal member 48 and the lower surface of the lowermost seal member 22. A second passage 50 is provided between the lower portion of the lowermost seal member 22 and the surface between the ram 10 and the gland ring 28. The passages 49 and 50 therefore connect the recess 47 and the lower portion of the lowermost seal member 22 with the low pressure chamber or space 41 to permit relief of pressure from the recess 47 which would cause leakage of fluid past the seal member 48 if this pressure should become excessively high, which would normally be the case if liquid was trapped in this chamber.

The retaining ring 29 has an annular recess 51 that receives the ledge portion 35 of the seal ring 31, and the gland ring 28 has an annular recess 52 that cooperates to receive a part of the ledge portion 35 to thereby retain the wiper ring 31 in position as illustrated in Fig. 4.

In operation, the elements of the seal structure are assembled as illustrated in Figs. 2 and 4. The conduit 32 is connected to the reservoir of the hydraulic system, or may if desired be connected to the suction side of the pump that supplies the hydraulic system. The bolts 30 are then tightened to move the retaining ring 29 and the gland ring 28 upwardly against the packing members 22, to compress the same. Sufficient compression is imparted to the packing members 22 to retain the hydraulic fluid under pressure in the chamber 16 at whatever pressure the hydraulic system is intended to operate. However, the packing members 22 are not compressed sufficiently to prevent all leakage of fluid between the ram 10 and the packing members 22, as has previously been done. Instead, the packing members 22 are compressed to a point at which a certain amount of leakage will occur between the surface of the ram 10 and the packing members 22. This leakage, or intentional flow of hydraulic fluid, between the ram 10 and the packing members 22 will permit a continuous flow of hydraulic fluid past the seal members 22 to thereby maintain a film of oil between the surface of the ram 10 and the packing members 22 whenever the pressure in the hydraulic system is high. The surface of the ram will therefore be lubricated when it reciprocates through the packing members 22. In addition the spaces 27 are charged with fluid which provide lubrication for the surface of the ram when the pressure in the chamber 16 is low, therefore giving the ram surface continuous lubrication regardless of whether high or low pressure is in the chamber 16.

The hydraulic fluid that flows past the seal members 22 enters the chamber 41. However,

since this chamber 41 is connected to the low pressure side of the hydraulic system, such as the reservoir, there can be no pressure in the chamber 41. The fluid which enters the chamber 41 will pass through the fitting 45 and the passage 46 to the conduit 32, and thence to the reservoir, or the low pressure side of the chamber. In any event, the fluid which enters the chamber 41 will not pass by the wiper ring 31 because the wiper ring frictionally engages the surface of the ram 10, and the ridges 33a on the wiper ring 31 squeegee fluid from the surface of the ram 10. Therefore when the ram 10 passes by the wiper ring 31 all surplus oil is removed therefrom and passed into the chamber 41. The portion of the ram that moves outwardly from the retaining ring 30 will therefore be relatively dry.

The frictional engagement of the wiper ring 31 upon the surface of the ram 10 is required only to cause movement of the fluid from the chamber 41 to the reservoir connected to the conduit 32.

The lower segments 33 of the wiper ring 31 produce a squeegee action upon the surface of the ram 10 to wipe the surface free of foreign particles when the ram moves in an upward direction as viewed in Figs. 1 and 2. This, therefore, prevents foreign particles from entering the space occupied by the packing members 22 so that the life of the packing members is greatly increased.

In order to permit the installation of the wiper ring of this invention upon presses that are already installed in the field, and to permit the functioning of the seal members in the presses installed in the field in accordance with the principles disclosed in this invention, certain modifications of the structure of the retaining members for the wiper ring must be produced to permit the use of existing parts in the presses that are in the field. Such a modified arrangement of structure is disclosed in Fig. 5 wherein the retaining ring for the seal members has been re-operated to permit installation of the wiper ring of this invention and thereby permit the conventional packing member to function in accordance with the principles of the invention. It is, of course, understood that a new retaining ring can be provided if desired.

In the arrangement listed in Fig. 5 the upper gland ring 60 is disposed between the ram 10a and the wall of the recess 14a provided in the lower end of the cylinder 12a in the same manner as heretofore described with regard to Fig. 2. At least, the upper gland ring 60 need not be changed from the existing construction of gland ring that is provided in the seal structures that are present in the presses now in use. The packing members 22a are identical with the packing members heretofore described with regard to Fig. 2 and function in the same manner.

Normally, the retaining ring 61 is provided with an extending annular portion 62 that engages the packing members 22 to apply pressure thereupon to seal upon the surface of the ram 10a, suitable nuts 63 being threaded upon the studs 64 for this purpose.

The usual retaining ring 61 is modified by providing a recess 65 to receive the seal member 48a similar to the seal member heretofore described with regard to Fig. 2, and which performs the same function as the seal member 48. The retaining ring 61 is also provided with a recess 66 to receive the wiper ring 31a that is in all respects

similar to the construction of the wiper ring 31 previously described with regard to Fig. 2. The wiper ring 31a is provided with an extending ledge portion 67 that is received in an annular recess 68 provided in the retaining ring 61, a ring member 69 being secured to the retaining ring 61 to hold the wiper ring 31a in position as illustrated in Fig. 5.

The space, or chamber, 70 provided above the wiper ring 31a, similar to the space 41 previously described with regard to Fig. 4, is connected to a passage 71 that in turn connects with a conduit 32a. The conduit 32a connects with a supply reservoir, or low pressure side of the hydraulic system, in the same manner as conduit 32 previously described.

The operation of the seal structure illustrated in Fig. 5 is the same as the operation of the seal structure previously described. Hydraulic fluid that moves along the wall surface of the ram 10a will be conducted from the chamber 70 into the passage 71 for return to a reservoir, or low pressure side of the hydraulic system, by means of the conduit 32a. During the upstroke of the ram 10a the wiper ring 31a will remove foreign particles from the surface of the ram to prevent them from entering the chamber in which the seal members 22a are located.

If it is desired to increase the degree of frictional surface engagement between the wiper ring 31a, or the wiper ring 31, such increase in frictional surface engagement can be obtained by placing a coiled spring member 75 around the body of the wiper ring as illustrated in Fig. 9. This increase in frictional engagement will prevent any seepage of oil between the wiper ring 31 and the surface of the ram 10 so that the lower portion thereof will work substantially free of oil.

If the increase in frictional engagement between the wiper ring and the ram is desired adjacent the lower portion of the wiper ring, the spring member 75 may be positioned around the lower portion of the body of the wiper ring as illustrated in Fig. 9. This will increase the effectiveness of the wiping action of the wiper ring upon the surface of the ram to remove foreign particles from it during the upward stroke of the ram.

If, however, the increase in frictional engagement between the wiper ring 31 and the surface of the ram 10 is desired for the purpose of preventing absolutely any seepage of oil past the wiper ring, the spring member can be positioned around the body of the wiper ring adjacent the upper edge thereof as illustrated by the spring member 75a shown in Fig. 6. The action of the spring member in this latter instance may be required when the oil that flows into the chamber 70 is required to be raised to a relatively high level, such as in those instances wherein the surge tank or reservoir is located on top of the head of the press.

In Figure 10, the ram 10b operates in the cylinder 12b, the ram 10b being the ram of the hydraulic press as heretofore described. An upper gland ring 20b is disposed between the ram 10b and the cylinder 12b against which the packing rings 22b are supported. The packing rings 22b are constructed similarly to the packing rings 22 heretofore described with regard to Figure 2.

The lower gland ring for compressing the packing rings 22 consists of a gland ring portion 100 that is an integral part with the supporting ring 101 that is secured to the cylinder 12b by

the bolts 102 extending through the supporting ring 101 into threaded engagement with the cylinder 12b. The gland ring portion 100 has a recess 103 that receives a packing member 104 of rubber-like material. The packing member 104 is preferably circular in cross-section, when in an uncompressed condition, and is of linear material so that any desired length thereof can be cut to encircle the ram and be positioned in the groove 103 with the ends thereof in abutting relationship.

A passage 105 extends between the surface of the ram 10b and the cylinder 12b to prevent development of high pressures above the packing member 103.

The retaining ring 101 has a recess 106 that receives a wiper ring 107 retained therein by means of the retaining ring 121 which when positioned in the recess 106, engages the outer periphery of the ram 10b.

The wiper ring 107 is more specifically shown in Figure 11 and consists of a body portion 108 that is provided with an arcuate concave surface 109 that engages the surface of the ram and applies pressure thereon to seal against the ram. A tongue 110 is carried by the body 108 of the wiper ring and is placed in a recess 111 in the ring 101 to locate the wiper ring in position, and retain the same on the ring 101. A plurality of longitudinally extending ridge portions 112 are formed in the face of the wiper ring to wipe the surface of the ram during its upward stroke, as illustrated in Figure 10. While the wiper ring 107 has been specifically mentioned as a ring member, yet it is to be understood that it is made from linear material that is cut to the desired length in the same manner as heretofore described with regard to the ring illustrated in Figure 3.

A recess 115 is provided in the ring 101 above the upper edge of the wiper ring 107 that receives a seal member 116. The seal member 116 is preferably circular in cross-section, when not under compression, and is formed of linear material that is cut to the desired length to encircle the ram 10b so that the ends of the member 116 abut one another.

An annular chamber 117 is formed between the ram 10b and the recess 115 in which the seal member 116 resides so that any pressure in the chamber 117 will tend to compress the resilient rubber-like seal member 116 and force the same against the surface of the ram 10b in direct proportion to the pressure existing in the chamber 117.

In accordance with the operation of the seal structure heretofore mentioned with regard to the other figures of the application, the seal members 22b are supplied with oil moving between the ram 10b and the seal members 22b. This oil collects in the chamber 117 and is directed to a reservoir chamber through the passage 119 and the connecting passage 120.

The wiper ring 107 and seal member 116 provide means whereby the ram below the wiper ring 107 is retained free of oil, and grit is prevented from entering the chamber retaining the sealing members 22b. Also, the seal member 116 provides means whereby oil in the chamber 117, when drained therefrom, can be lifted to a considerable height so as to return the oil to an overhead reservoir on the hydraulic press, any pressure of the oil in the passage 120, and thus the chamber 117, as a result of the head of oil from the overhead reservoir will result in apply-

ing sufficient pressure upon the seal member 116 to cause the same to apply sufficient pressure upon the surface of the ram 10b to prevent leakage of oil between the ram and the seal member and lift the oil to the overhead reservoir.

While the structural arrangement of the apparatus disclosed and described herein constitutes preferred forms of the invention, it is to be understood that the apparatus is capable of structural illustration without departing from the spirit of the invention, and that all modifications that fall within the scope of the appended claims are intended to be included herein.

Having thus fully described my invention, what I claim as new and desire to secure by Letters Patent is:

1. In combination, a hydraulic cylinder, a ram reciprocable in said cylinder and extending from one end thereof, and a seal around said ram that includes, a packing member disposed between said ram and said cylinder, a retaining ring for retaining said packing member in position between said ram and said cylinder and for applying pressure thereupon to produce frictional engagement between said ram and said cylinder to such an extent that a determined and controlled flow of hydraulic fluid will pass between said ram and said packing member, a recess in said retaining ring containing a seal member contacting the wall of said cylinder to prevent fluid from passing along the cylinder wall beyond said sealing member, a wiping means frictionally engaging said ram and positioned for wiping the fluid from the surface of said ram after the fluid has passed between said packing member and the ram and for directing the fluid from the surface of the ram into a collecting chamber, a fluid collecting chamber positioned between said wiping means and said packing member to collect fluid passing between said packing member and said ram and which is directed thereinto by said wiping means, means for conducting fluid collected in said chamber away from the same, and a passage connecting said recess with said collecting chamber to relieve fluid pressure from said recess.

2. In combination a hydraulic cylinder, a ram reciprocable in said cylinder and extending from one end thereof, and a seal around said ram that includes, a packing member disposed between said ram and said cylinder, a retaining ring for retaining said packing member in position between said ram and said cylinder and for applying pressure thereupon to produce frictional engagement between said ram and said cylinder to such an extent that a determined and controlled flow of hydraulic fluid will pass between said ram and said packing member, a resilient wiping means having a plurality of annularly disposed recesses therein on both sides of the annular center line of said wiping means which provide ledge segments and which are disposed in oppositely directed positions on opposite sides of the annular center line of said wiping means to thereby be positioned against the direction of movement of the ram when reciprocating in the cylinder and for frictionally applying pressure upon the surface of said ram, said wiping means being positioned for wiping the fluid from the surface of said ram after the fluid has passed between said packing member and the ram and for directing the fluid from the surface of the ram into a collecting chamber, a fluid collecting chamber positioned between said wiping means and said packing member to collect fluid passing between said packing member and said ram and which is directed thereinto by said

11

wiping means, means for conducting fluid collected in said chamber away from said ram, and a resilient seal member positioned adjacent said wiping means and between the wiping means and said packing member and frictionally applying pressure upon the wall of said cylinder to prevent fluid from passing along the cylinder wall beyond said sealing member.

OTTO M. SUMMERS.
